R. S. GANDY.

METALLIC RAILWAY TIE AND FASTENER.

APPLICATION FILED SEPT. 4, 1915.

1,173,658.

Patented Feb. 29, 1916.

UNITED STATES PATENT OFFICE.

RODNEY S. GANDY, OF VINELAND, NEW JERSEY.

METALLIC RAILWAY-TIE AND FASTENER.

1,173,658.

Specification of Letters Patent. Patented Feb. 29, 1916.

Application filed September 4, 1915. Serial No. 49,068.

To all whom it may concern:

Be it known that I, RODNEY S. GANDY, a citizen of the United States, residing at Vineland, in the county of Cumberland and 5 State of New Jersey, have invented certain new and useful Improvements in Metallic Railway-Ties and Fasteners, of which the following is a specification, reference being had to the accompanying drawings.

10 This invention comprehends certain new and useful improvements in metallic railway ties and fasteners and has for its primary object a durable and efficient construction of device of this character wherein the tie will possess to a marked degree the characteristics of simplicity, strength, durability, capability of being easily ballasted and 15 rigidity, and wherein the fastening devices will so contact with the tie as to hold the rail securely and be capable of ready application and withdrawal or removal as required. And the invention also aims to generally improve devices of this character so as to render them more useful and commercially desirable.

20 With these and other objects in view as will more fully appear as the description proceeds, the invention consists in certain constructions, arrangements and combinations of the parts that I shall hereinafter 25 fully describe and claim.

For a full understanding of the invention reference is to be had to the following description and accompanying drawing, in 30 which—

Figure 1 is a longitudinal sectional view through a metallic tie and rail fastener embodying the improvements of my invention, parts being shown in side elevation. Fig. 35 2 is a top plan view with parts in section and other parts broken away. Fig. 3 is a similar view with the rail fastening devices shown in section. Fig. 4 is a detailed view of one of the fastening devices; and Fig. 5 is a 40 transverse sectional view through the tie.

45 Corresponding and like parts are referred to in the following description and designated in all of the views of the accompanying drawing by like reference characters.

50 Referring to the drawing, the numeral 1 designates the top of my improved hollow metallic tie, 2 the downwardly diverging sides of the tie and 3 the bottom thereof. This tie may be formed out of steel and 55 stamped and shaped by suitable machinery, as is evident, and may be of any desired size

or proportion of parts and of a length to support any desired number of rails, transversely considered. It is formed at each end or at any other suitable points, according to the number of rails the tie is designed to support, with a number of openings 4, the same being preferably stamped out of the sheet at or before the same is formed into the completed tie and the openings being 60 preferably arranged in series of four, having a quad-rectangular disposition, whereby either diagonally disposed pair may be used in connection with the fastening device hereinafter described, to hold the rail or whereby all four may be used if desired, where extreme rigidity and very secure fastening means are required as, for example, around sharp curves.

Each opening 4 includes a middle substantially circular portion 5 terminating at each side in a preferably oblong end 6, as clearly illustrated in the drawing.

Coacting with the openings 4 are the locking devices. Each locking device comprises 80 a key 7 which is formed at its upper end with an upwardly projecting preferably rectangular lug 8, with a head 9 below the lug, said head being formed with a beveled lug 10 designed to extend over the adjoining 85 base flange of a rail, with a flat surface 11 on the lower side of the head adapted to rest upon the top 1 of the tie, with a substantially round neck 12 below the head and adapted to be seated in and accommodated 90 by the middle portion 5 of a slot 4 and below said neck with a lateral elongated portion 13, the upper surface of which constitutes shoulders projecting in opposite directions from the neck, the laterally widened 95 portion at the lower end of the key being designed for insertion in and through the slot or opening 4, whereupon, when the shoulders 13 pass below the lower wall of the top 1 of the tie the key may be turned 100 substantially at right angles to the length of the slot and engage the base flange of the rail, the shoulders 13 obviously preventing any accidental retraction of the key and assuring that the rail will be securely held in 105 place, until the key is turned.

In order to prevent the key from being accidentally turned, I form a vertical groove or recess 14 in the back of the head 9, said recess merging into a flattened portion 14' 110 at the back of the neck, the latter, together with the recess 14 being substantially co-ex-

tensive in width to the width of the end of the slot 4 with which it registers. Thus a pin 15 may be readily inserted into the adjoining end of the slot and be received in 5 the recess 14 whereby it will securely prevent the key from being accidentally turned and the rail will thus be held in a very secure and rigid condition.

From the foregoing description in connection with the accompanying drawing, it will be seen that I have provided a very durable, rigid and efficient construction of railway tie and fastener whereby the rails may be very quickly held in place without 10 the necessity of driving spikes and whereby the rails, when once in position will be very securely held, without any danger of becoming accidentally deranged.

While the accompanying drawing illustrates what I believe to be the preferred embodiment of my invention, it is to be understood that the invention is not limited thereto but that various changes may be made in the construction, arrangement and 20 proportions of the parts without departing from the scope of the invention as defined in the appended claim.

Copies of this patent may be obtained for five cents each, by addressing the "Commissioner of Patents, Washington, D. C."

I claim:

The combination with a tie formed with slots for the reception of rail holding devices, each slot including a widened portion and a reduced end, of a rail holding key provided with a head adapted to engage the base flange of a rail, with a round neck receivable in the widened portion of the slot and with shoulders below the neck adapted to extend through the slot for the purpose specified, the head being formed on its rear side with a vertically disposed recess and the neck at its rear being formed with a flattened portion forming a continuation of the recess, and a pin adapted to be slipped into one end of the slot back of the key and receivable in said recess and lying against the flattened portion of the neck whereby to 30 secure an increased bearing surface against the key, as set forth.

In testimony whereof I hereunto affix my signature in the presence of two witnesses.

RODNEY S. GANDY.
